(57) **CLAIM**

The ornamental design for a nose section for a car body, as shown and described.

DESCRIPTION

FIG. 1 is a front-right perspective view of the nose section for a car body, showing my new design;

FIG. 2 is a rear-left perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines shown in the drawings illustrate portions of the nose section for a car body that forms no part of the claimed design.
